UNITED STATES PATENT OFFICE.

ABRAHAM B. DEPENY, OF HAMBURG, IOWA.

IMPROVEMENT IN HARROWS.

Specification forming part of Letters Patent No. **133,212**, dated November 19, 1872.

To all whom it may concern:

Be it known that I, A. B. DEPENY, of Hamburg, in the county of Fremont and in the State of Iowa, have invented certain new and useful Improvements in Harrow; and do hereby declare that the following is a full, clear, and exact description thereof, reference being had to the accompanying drawing and to the letters of reference marked thereon making a part of this specification.

The nature of my invention consists in the construction and arrangement of a harrow, as will be hereinafter more fully set forth.

In order to enable others skilled in the art to which my invention appertains to make and use the same, I will now proceed to describe its construction and operation, referring to the annexed drawing, in which—

Figure 1 is a plan view, and Fig. 2 a side elevation of my harrow.

A represents a center beam, at or near the front end of which are top and bottom cross-bars B B. On each side of the center beam A, between the ends of the cross-bars, is pivoted a side beam, C. A short distance in rear of the cross-bars B B, on the beam A, are similar but shorter cross-bars B' B', having other side beams C' C' pivoted between them—one on each side of the center beam. On top of the center beam A, at or near the rear end, are pivoted two links, D D, which extend in opposite directions and pass over screw-bolts *a* *a*, projecting upward from the upper sides of the side beams C' C'. On top of each of the outer side beams C is pivoted a similar link, D', which extends inward over the said screw-bolt *a* underneath the link D, and the whole fastened by means of a lever-nut, E, a wash-

er, *b*, being first placed underneath said nut on the bolt. By this means the side beams C C and C' C' may be placed at any angle with the center beam that may be desired, or, in other words, their rear ends may be extended or contracted at will. Upon the outer sides of the side beams are fastened a series of teeth, G G, constructed as shown in Fig. 2, their upper ends being slotted longitudinally, and a screw, *d*, passed through said slot into the side beam; and a washer, *e*, is placed on said screw between its head and the tooth. By this means the teeth may be raised and lowered at will, and also set at any angle slanting either forward or backward. The teeth may also be reversed if desired. Cultivator-teeth J J, having their upper ends or shanks slotted the same as the harrow-teeth, may be attached to the inner side beams C' C' in the same manner, so that by removing the outer side beams C C I will have a combined harrow and cultivator. H represents the handle attached to the center beam A.

Having thus fully described my invention, what I claim as new, and desire to secure by Letters Patent, is—

The reversible and adjustable teeth G G and J J, slotted as described, and fastened by means of screws *d* *d*, substantially as herein set forth.

In testimony that I claim the foregoing I have hereunto set my hand this 20th day of August, 1872.

ABRAHAM B. DEPENY.
